(57) **CLAIM**

The ornamental design for a changeable multiple position jewelry, as shown and described.

DESCRIPTION

FIG. 1 is a front view of a changeable multiple position jewelry in one position;

FIG. 2 is a rear view of my changeable multiple position jewelry of FIG. 1;

FIG. 3 is a left side view of my changeable multiple position jewelry of FIG. 1;

FIG. 4 is a right side view of my changeable multiple position jewelry;

FIG. 5 is a top view of my changeable multiple position jewelry of FIG. 1;

FIG. 6 is a bottom view of my changeable multiple position jewelry of FIG. 1; and,

FIG. 7 is a front view of my changeable multiple position jewelry of FIG. 1 in another position.

The dot/dash broken lines seen in FIG. 2 and the surfaces they enclose illustrate portions of the changeable multiple position jewelry that form no part of the claimed design. The unillustrated internal side views in FIG. 7 form no part of the claimed design.

The broken line showing of a chain in FIGS. 1 and 7 depicts environmental structure associated with the changeable multiple position jewelry in a condition of use and forms no part of the claimed design.
